(57) **CLAIM**

I claim the ornamental design for a body temperature screening control unit, as shown and described.

DESCRIPTION

FIG. 1 is a perspective view of the body temperature screening control unit shown with a temperature sensor; FIG. 2 is a front perspective view of the body temperature screening control unit of FIG. 1;

FIG. 3 is a rear perspective view thereof;

FIG. 4 is a top plan view thereof;

FIG. 5 is a front elevation view thereof;

FIG. 6 is a left side elevation view thereof;

FIG. 7 is a right side elevation view thereof;

FIG. 8 is a rear elevation view thereof; and,

FIG. 9 is a bottom plan view thereof.

The broken lines in the figures depict portions of the body temperature screening control unit that form no part of the claimed design.
